(57) **CLAIM**

The ornamental design for a game and computer system safety stand, as shown and described.

DESCRIPTION

FIG. 1 is a perspective view of a game and computer system safety stand showing our new design in the upright position and facing left;

FIG. 2 is a perspective view thereof, in a partially assembled state;

FIG. 3 is a bottom perspective view thereof, in a partially assembled state;

FIG. 4 is a side view thereof, in a partially assembled state;

FIG. 5 is an end view thereof, in a partially assembled state;

FIG. 6 is a top view of the stand portion of the design, wherein the base units are omitted for ease of illustration;

FIG. 7 is a bottom view of the stand portion of the design, wherein the base units are omitted for ease of illustration;

FIG. 8 is a top view of FIG. 1;

FIG. 9 is a bottom view of FIG. 1;

FIG. 10 is a top view of one a base unit shown separately for ease of illustration, both base units having the same dimensions thereof; and,

FIG. 11 is a bottom view of a base unit shown separately for ease of illustration, both base units having the same dimensions.

A game and computer system safety stand where the stand functions to support game and computer systems keeping them from falling over, providing proper air flow for cooling and proper ventilation in order to reduce fire hazard of over-heated systems.
